UNITED STATES PATENT OFFICE.

MAX SCHNUG, OF BONDUEL, WISCONSIN.

LIMP-SETTING DEVICE.

1,176,490.

Specification of Letters Patent. Patented Mar. 21, 1916.

Application filed November 2, 1915. Serial No. 59,246.

To all whom it may concern:

Be it known that I, MAX SCHNUG, a citizen of the United States, and a resident of Bonduel, in the county of Shawano and State of Wisconsin, have invented certain new and useful Improvements in Limb-Setting Devices, of which the following is a specification.

My present invention, designed for setting fractures of the upper leg or hip, right, left, or both, and in the reduction of which it is necessary to have the body elevated in order to be enabled to put a bandage or plaster cast around leg, hip, or back, and at the same time to maintain the leg or legs under tension and in proper anatomical line, is an improvement over the form shown and described in Letters Patent of the United States, No. 1,148,996, issued to me on the 3rd day of August, 1915, and one of the main objects is to provide such an apparatus which may be quickly assembled and unassembled whereby, when not in use, the parts may be stored within a small compass and be readily portable.

A further object is to be enabled to place a patient upon the table of the apparatus with certain of the parts of the latter not in position whereby no unnecessary bending of the patient's limbs will occur, these parts being placed in position after the patient has been properly and comfortably arranged.

A further object is to be enabled to utilize the particular members of the device for particular fractures because of their detachability, and also to provide a comfortable rest for the uninjured leg if but one leg or hip is fractured.

My invention is fully described in the following specification, of which the accompanying drawings form a part, in which like characters refer to like parts in each of the views, and in which:—

Figure 1 is a perspective view of the apparatus fully assembled for use, partly broken away; Fig. 2 is a longitudinal section thereof taken on the line 2—2 of Fig. 3; Fig. 3 is a section taken on the line 3—3 of Fig. 2; Fig. 4 is a section taken on the line 4—4 of Fig. 2; Fig. 5 is a section taken on the line 5—5 of Fig. 2; Fig. 6 is an enlarged, fragmentary, view thereof to show the manner of connecting certain parts of the frame; and Fig. 7 is a similar view of a detail of the apparatus.

In the drawings forming part of this application I have shown a main frame formed by longitudinal strips 10 and 11 bolted or otherwise secured to transverse strips 12 and 13, the former of which has a plate 14 secured thereto and to which, in turn, a strip 15 is hinged, whereby said strip may be folded against said plate when the apparatus is not in use. The strip 15 has three notches 16 cut into the upper edge thereof and the plate 14 is provided with two pairs, 17 and 18, of sockets for the reception of two pairs, 19 and 20, of detachable posts provided, each, with adjustable slide-blocks 21 and 22, respectively, carrying screws 23 and 24 having bandage securing means 25 and 26, respectively, at their inner ends and with suitable handles at their outer ends. The pairs of posts support a horizontally arranged bar 27 having two notches 28 cut therein and covered by plates 29, as shown in detail in Fig. 7, for the reception of detachable bars 30 and 31, and it will be noted that, when the longitudinal strips 10 and 11 are in place, they lie beneath the hinged strip 15 and prevent further opening movement thereof with respect to the plate 14, the posts 19 and 20 preventing closing movement of said strip 15.

The side strips 10 and 11 carry, each, at their inner ends, a perforated block 32 and a vertically arranged socketed block 33, a socket being provided in the top of each for the reception of detachable posts 34 and at the rearward side of each is a socket for the reception of side rods 35, detachably, and the outer ends of which rest in the respective notches 16 and serve to support a sheet 36 of canvas or the like, said sheet being provided with pockets for the rods 35 and for another rod 37 centrally arranged, the outer end of which rests in the respective notch 16 and the inner end of which is supported by a plate 38, whereby the sheet 36 is held several inches above the main frame.

Carried centrally of the transverse strip 13, in a socket 39, is a post 40 of tubular form to receive, at its top, a pin 41 carried by a transverse bar 42 having sockets at its ends for the reception of the upper ends of the posts 34 and said bar 42 supports the inner ends of the bars 30 and 31, each of which has a pin 43 for detachable engagement therewith.

The main body support for the patient consists of two side strips 44 having forked

angle plates 45 at their lower ends adapted for adjustable connection with the perforated blocks 32, perforated legs 46 being in adjustable connection with the outer 5 upper ends of said strips and suitable braces 47 being provided for the legs, and it will be seen that, because of the perforated blocks 32 the body support may be adjusted toward or from the main frame and the 10 inclination thereof may be adjusted by means of the legs 46. A transverse bar 48 holds the outer ends of the strips 44 in desired relationship with each other and also serves as a support for a head-rest 49 and for an 15 adjustable strap 50.

The strap 50 is held at one end by a bolt 51 held in a bracket 52 beneath the bar or plate 48 and is passed thence to the outer edge of the said bar, around said edge, and 20 toward the transverse strip 18, above the bar 48 but beneath a canvas sheet 53 carried by the side strips 44, and it will be seen that this canvas sheet 53 may be adjusted as to yield due to the weight of a body thereon 25 by changing the tension of the strap 50. The inner end of this strap is passed over a bolt 54 carried by a sheet metal casing 55 and to a roller 56, having a slot therein to receive the end of the strap 50, Fig. 2, rotatable in said casing but held in adjusted 30 position by means of a ratchet wheel 57 on said roller and a spring actuated pawl 58 on the casing 55, the outer end of the roller 56 being angularly formed so as to be engaged by an angularly socketed crank, not 35 shown, whereby the strap 50 may be tightened or loosened at will.

From the foregoing and from the drawings it will be readily seen that the apparatus 40 may be assembled and unassembled at will, the strips, plates, bars, and rods, being separable from each other, the legs and braces being separable, and the canvas sheets and the strap 50 being detachable, 45 whereby the parts, when not in use, will occupy a relatively small space and may be readily carried to a point distant from the physician's office. All fractures are set by means of extension. In order to give a clear 50 conception, how extension is produced by the aid of this apparatus, I wish to explain as follows: Both legs, the injured as well as the healthy one, receive adhesive straps on both sides of the leg, held by a circular 55 band, applied in such a way that the prominences of the bone at knee or ankle joint, hold the same in proper place, and which are strong enough to stand the pull of extension. These adhesive straps are fastened according to the kind of fracture treated either to the knee or ankle joint. These adhesive straps are fastened on the other end 60 to the head pieces 25 and 26 of the screws 23 and 24. Both legs, the injured as well as the healthy one, are fastened this way,

in order to keep the body in proper balance. The post 40 holds the patient in place to limit his possible movement toward the foot end of the apparatus. Then traction is made by the extension screws 23 and 24. 70 The rotation of the screws 23 and 24 does not move the head pieces 25 and 26, as the latter run on a swivel joint, and thereby keeps the injured leg perfectly quiet. The apparatus is removed after the fracture is 75 set and the permanent dressing or plaster cast is applied. The arrangement of this apparatus makes it possible to put on a plaster cast due to the elevation of the body and provides plenty of room around the injured 80 limb. If the plaster cast is made a tight fit, it holds the fracture in place, without putting any weight or traction on the leg after the apparatus is removed.

The apparatus can be used for all fractures of the hip, upper and lower leg. It is also adapted for all sizes of adults and children. The lower part of the body rests only on the strap 50; there is nothing else in the way. If a plaster cast is put around the 85 hips and back I put it over the strap 50. After the patient is ready, the said strap is cut off on both sides of the plaster cast and the patient removed from the apparatus to the bed. 90

In practice, when a fracture of the kind referred to is to be treated, the apparatus may be assembled with the exception of the bars 30, 31, and 42, and the posts 34 and 40, and the patient placed thereon; the post 40 may now be placed in position at the crotch of the legs of the patient to limit his possible movement toward the foot of the apparatus, the inclination of the body 100 support arranged, and the strap 50 placed under desired tension, after which the posts 34 and bars 30, 31, and 42 may be assembled, a bandage or strap passed around the ankle of the injured leg and to the respective bandage engaging means on the respective 105 slide-block 21 or 22 and tension applied by means of the screw 23 or 24. When the fracture has been set, the plaster-cast or bandages may be passed around the injured leg, and suitable slings employed depending 110 from either or both of the bars 30 and 31 to arrange the injured leg in the most comfortable position as well as in the correct anatomical line, whereas the uninjured leg may rest at ease on the canvas sheet 36, the body 115 being supported in comfortable position on the canvas sheet 53 in the adjusted position of the strip 50.

No effort has been made to illustrate a patient in position on my apparatus for the 120 reason that fractures at different points would require different illustrations, and these will be obvious to any person skilled in the art to which this invention appertains. In practice, when a fracture of the 125 130

kind referred to is to be treated, the apparatus may be assembled with the exception of the bars 30, 31 and 42, and the posts 34 and 40, and the patient placed thereon; the post 5 40 may now be placed in position at the crotch of the legs of the patient to limit his possible movement toward the foot of the apparatus, the inclination of the body support arranged, and the strap 50 placed under desired tension, after which the posts 10 34 and bars 30, 31 and 42 may be assembled. Adhesive straps secured to the knee or ankle joint as explained before are fastened at the other end to the head pieces 25 and 26. The 15 leg is also held in position by one or more slings to bars 30 and 31. Having the leg in proper position extension is made now by rotating the extension screws 23 and 24. Both hands are free now to examine the leg 20 or hip and see if the fracture is properly set, see if everything is in the proper anatomical line, and corrected if needed. The leg is held now tied as in a vise and no movement thereof is possible. Then remove the 25 side rods 35 and center rod 37 as well as the canvas sheet 36. Having this removed gives plenty of room around the legs, hip and back to put on the plaster cast or other permanent dressing. If the plaster cast fits 30 snug, it is not necessary to put on any weight or extension afterward. The dressing is put on over the strap 50. When the plaster cast is dry and hard the patient is removed from the apparatus and put to bed. Before doing 35 this this strap 50 has to be cut off on both sides of the plaster cast. The perfect rest of the leg from below and above, and the gradual pull to set the leg, give so little pain to the patient that in most cases no anesthetic is required.

My invention is simple in construction and use, is well adapted for use in country practice, as well as for city practice or hospitals.

While I have shown a preferred form of 45 construction, it will be apparent that I do not confine myself thereto but may make changes thereover, within the scope of the following claims, without departing from the spirit of my invention or sacrificing its 50 advantages.

Having fully described my invention, what I claim as new, and desire to secure by Letters Patent, is:—

1. A limb setting device, comprising a 55 frame, a body support including a strap, pivoted thereto, a vertical rod arranged centrally of said device at the junction of said

frame and body support to limit the movement of a patient in one direction, away from said body support, and means for 60 causing tension on an injured leg.

2. A limb setting device, comprising a frame, a body support including a strap, pivoted thereto, means for preventing a patient from moving away from said body support, means for applying tension to his legs, and means for varying the yielding of said 65 body support to the weight of said patient.

3. A limb setting device, comprising a frame, a body support, including a strap, 70 pivoted thereto, a canvas sheet above said frame, means for holding the same in such position, a canvas sheet on said support, means for controlling the yielding thereof to the weight of a patient, and means for 75 preventing movement of the patient away from said body support.

4. A limb setting device, comprising a frame, a plurality of longitudinally arranged rods held at a desired distance thereover, a canvas sheet held by said rods, a body support pivoted to said frame, a head rest thereon, a canvas sheet thereon, means, including a strap, for controlling the yielding thereof to the weight of a patient, and 85 means for preventing the movement of the patient away from said body support.

5. A limb setting device, comprising a frame formed of detachable members, a detachable canvas sheet stretched thereover, a 90 body support pivoted to said frame, a canvas sheet stretched thereon, means, including a strap, for maintaining said last named sheet under adjustable tension, means for preventing a patient from moving away 95 from said body support, and means for applying tension to the legs of said patient.

6. A limb setting device, comprising a frame, a body support pivoted thereto, means for preventing a patient from moving 100 away from said support, means for inclining said support at a desired angle, a canvas sheet on said support, a strap for holding said sheet in position, and means for applying tension to said strap to control 105 the yielding of said sheet to the weight of a patient.

In testimony whereof I have signed my name to this specification in the presence of two subscribing witnesses.

MAX SCHNUG.
